UNITED STATES PATENT OFFICE.

JOHN L. ACKLEY, OF PENN YAN, NEW YORK.

EXTENSION-TOWER.

1,076,539.

Specification of Letters Patent. Patented Oct. 21, 1913.

Application filed February 26, 1912. Serial No. 680,085.

To all whom it may concern:

Be it known that I, JOHN L. ACKLEY, a citizen of the United States, residing at Penn Yan, in the county of Yates and State 5 of New York, have invented a new and useful Extension-Tower, of which the following is a specification.

This invention has reference to improvements in extension towers which may be employed for portable or stationary fire escapes, water towers, elevators, and other purposes, and its object is to provide a tower which may be extended or telescoped to any desired extent within its range of 10 movement and is especially adapted to be mounted upon a truck of the automobile type for transportation from place to place, and when used as a fire escape may carry 15 the net designed to receive persons from otherwise inaccessible points in buildings 20 without the necessity of an extended fall to the net.

While the invention in some of its particulars is not limited to a portable structure, nor to a fire escape, the description of 25 the invention will be largely directed to the invention as embodied in a fire escape, and to this end the invention comprises a suitable automobile truck on which there is 30 mounted a frame provided with corner posts capable of being extended or telescoped, these corner posts carrying a suitable net, which latter by the extension of the corner 35 posts may be brought in easy jumping distance to the point from which it is desirable to rescue a person or persons, whereby the extent of fall may be so reduced that there 40 is no danger of injury to the person landing in the net.

By the present invention provision is 45 made for the elevation or lowering of the tower by the propelling power of the automobile truck through devices which may be controlled at will, and in addition to the net there may be provided a supplemental 50 border net movable into position as the tower is elevated to increase the spread of the net, whereby any extended jump by the person to be rescued in order to reach the net is avoided, while the net extension is so arranged that a person landing on the extension will be directed into the main body of 55 the net from which accidental escape is impossible.

When the device is employed in connection with a fire escape an appropriate num-

ber of separate but operatively connected telescoping devices are provided to carry the net or other means for receiving the persons, but when the invention is employed for some other purposes a single one of the telescoping devices may be sufficient.

While in the drawings there is shown a practical embodiment of the invention, and from the drawings taken in connection with the accompanying specification of which the drawings form a part, there may be obtained a complete understanding of the invention, the latter is by no means confined to any strict conformity with the showing of the drawings, for it is susceptible of various changes and modifications without making any material departure from the salient features of the invention.

In the drawings:—Figure 1 is a side elevation of a portion of an automobile truck with the invention applied in the form of a fire escape. Fig. 2 is a plan view of the structure shown in Fig. 1, some parts of the truck being omitted. Fig. 3 is a section on the line 3—3 of Fig. 1 but drawn to a larger scale. Fig. 4 is a section on the line 4—4 of Fig. 1 but drawn to a larger scale. Fig. 5 is an elevation of the structure of Fig. 4 as viewed from the right hand side thereof with some parts broken away and other parts in section on the line 5—5 of Fig. 4. Fig. 6 is a section on the line 6—6 of Fig. 4. Fig. 7 is a rear elevation of the device of Fig. 1. Fig. 8 is an elevation of the front 75 end of the automobile truck shown in Fig. 1 with some parts omitted.

Referring to the drawings, there is shown a frame 1 which may be of general rectangular shape, and this frame is carried by 80 wheels 2, 3, through the intermediary of springs 4 and front and rear cradles 5, 6, respectively, said cradles being connected by a pivot 7 to a suitable portion of the frame 1, so that by mechanism to be described the frame 1 may be rocked on a longitudinal 85 axis coincident with the pivots 7 with respect to the wheels 2 and 3. The manner of supporting the frame 1 is not material to the present invention and hence no special 90 detailed description thereof is deemed necessary, and the showing of the drawings may be taken as typical of any supporting means for the frame 1, whether portable 95 or not.

In the drawings the frame 1 is provided with toothed arcs 8 at appropriate points,

and these arcs are engaged by pinions 9 on a shaft 10 which may extend from front to rear of the vehicle or truck, the said shaft 10 being provided at one end, preferably the 5 rear end, with a crank 11 by means of which the shaft may be rotated at will. The purpose of this structure is to permit the rocking of the frame 1 to either tilt or to level it when the truck is tilted on an uneven support.

The truck is assumed to be provided with a prime mover, such as an explosion engine, commonly employed in automobile trucks, and the engine is assumed to be coupled to 15 a drive shaft 12 which may extend longitudinally of the frame 1 and is connected by a universal joint 13 to a continuation 14 extended to reversing gear typified by a casing 15, and as such reversing and speed 20 changing gear may follow the usual practice in automobiles, no attempt has been made to illustrate any such gearing further than to show its outer casing. From the 25 gearing typified by the casing 15 the power shaft is continued to the rear axle 16 of the truck, which axle is assumed to drive the wheels 2. The power shaft 14 at an appropriate point carries a bevel gear 17, and spaced from the bevel gear 17 is another 30 bevel gear 18 also mounted on the power shaft.

The frame 1 carries two journal frames 19 and 20 in which is mounted a counter-shaft 21 having suitable bearings in the journal frame 20 and also in the journal frame 35 19, the shaft between these frames including a universal coupling 22, so that the end of the shaft mounted on the frame 19 may be moved with relation to the portion of the 40 shaft mounted in the frame 20. The end of the shaft mounted in the frame 19 carries a bevel gear wheel 23 designed to mesh with either pinion 17 or 18, but not both at the same time, and for this purpose the end of 45 the shaft 21 carrying the gear wheel 23 is provided with a bearing 24 on the frame 19 in which it may be moved about the universal coupling 22 to carry the gear wheel 23 into mesh with either pinion 17 or 18. 50 The adjustable end of the shaft 21 is connected by a link 25 to an arm 26 on a rock shaft 27 traversing the frame 1 and at one end provided with an operating lever 28 by means of which the shaft 27 may be rocked 55 in one direction or the other to shift the gear wheel 23.

The shaft 21 extends beyond one side of the frame 1 and there carries a gear wheel 29, which in turn meshes with another gear 60 wheel 30 on a counter-shaft 31 extending transversely of the frame 1 and suitably journaled thereon. The shaft 31 carries a bevel pinion 32 meshing with another bevel pinion 33 on one end of a shaft 34 extending lengthwise of the frame, adjacent one

side thereof, the shaft 34 having a journal bearing carried by the frame 20. That end of the shaft 34 remote from the pinion 33 carries another bevel pinion 35 meshing with a bevel pinion 36 on a shaft 37 traversing the frame 1 near what may be termed the rear end of the frame and suitably journaled therein.

The gear wheel 30 on the shaft 31 is suitably shaped to form one member of a clutch, 75 while mounted on the shaft 31 are clutch shoes 38 in operative relation to the clutch portion of the gear 30, the shoes 38 being carried by toggles 39 in turn connected to a sleeve 40 keyed to the shaft 31 and controlled by a yoke 41 carried by a lever 42 whereby the sleeve 40 may be shifted lengthwise of the shaft 31. The sleeve 40 also carries other clutch shoes 43 by toggles 44 and these clutch shoes are in operative relation to a clutch member 45 secured to a fixed part of the apparatus, as will hereinafter appear, wherefore the clutch member 45 and the clutch shoes 43 constitute a brake for a purpose which will also presently appear. 80 The parts are so proportioned that when the sleeve 40 is in an intermediate position the clutch shoes 38 and 43 are both inactive and may rotate with the shaft 31, or the latter may be at rest while the gear wheel 30 is 85 rotating.

When the gear wheel 23 is in engagement with one of the pinions 17 or 18, say the pinion 17, and the prime mover of the automobile is in motion, the shaft 21 is rotated in one direction and the gear wheels 29 and 30 participate in such rotative movement. If, now, the clutch shoes 38 be moved into engagement with the clutch portion of the gear wheel 30, the rotative movement of the gear 30 is imparted to the shaft 31 and through the intermediary of the shaft 34 to the shaft 37. If the gear wheel 23 engages the pinion 18 instead of the pinion 17, the direction of rotation of the shaft 21 is reversed and the direction of rotation of the parts driven by the shaft 21 is also reversed. If the gear wheel 23 be placed in an intermediate position between the pinions 17 and 18, then no power is transmitted from the prime mover to the shaft 21. If a force be applied to the shaft 31 tending to rotate the same when uncoupled from the gear 30, this force may be resisted by moving the brake shoes 43 into engagement with the fixed brake member 45 and the rotation of the shaft 31 may be slowed or stopped, in accordance with the braking force. The two shafts 31 and 37 are so connected by the intermediate shaft 34 that they will rotate in the 110 same direction.

Mounted at suitable points on the frame 1, and in the particular showing of the drawings near the rear ends of the side members of the frame and at other points toward the 115

front of the side members of the frame, are posts 46 each composed of spaced side members 47, 48, joined at appropriate intervals by spacing straps 49, the post 5 therefor being a hollow structure and it is to the side member 48 of this post that the brake member 45 is secured, as by brackets 50, to one of which one end of the lever 42 is pivoted, the other end of this lever being 10 connected to one end of a pair of joined links 51, the other end of which joined links is pivoted to the side member 48 of the post 46. The lever 42 is urged constantly in one direction by a contractile spring 52 interposed between and connected to the lever and the post 46. Extending transversely of the links 51 at their point of connection and in underriding relation to these links is a lever 53 at one end carried pivotally by 15 a bracket 54 and at the other end provided with a suitable handle whereby the lever may be readily manipulated. Connected to the links 51 at their junction point is one end of a chain or other like member 55, the 20 other end of which is connected to one end of a lever 56 pivoted to the side member 48 at a higher point than the lever 53, the lever 56 answering a purpose to be hereinafter explained.

30 Housed within the post 46 are telescoping members 57, 58, respectively, each made up of side plates and connecting yokes, which latter will be referred to as needed in the following description, it being understood 35 that the members 57 and 58 are of hollow construction to fit one within the other and while only two telescoping members are disclosed in the drawings for the sake of simplicity of illustration, it will be understood 40 that any number of these telescoping members may be employed, the post 46 being appropriately enlarged where more telescoping members are employed. The lower end of the post 46 is traversed by the shaft 31 and within the post this shaft carries a sprocket wheel 59 having a hub 60 on one side thereof, the sprocket wheel being displaced to one side of the center line of the post. Mounted on the shaft 31 as a pivot 45 is a yoke 61 in straddling relation to the sprocket wheel 59 and the hub 60, and the yoke carries one end of an arm 62 extending upwardly through the post 46, it being understood that the post 46 is in operation 50 substantially upright. The other or upper end of the arm 62 is formed with a yoke 63 between the ends of which there extends a shaft 64 on which is mounted a sprocket wheel 65 and a pinion 66, the sprocket wheel 55 and pinion moving together. Fast to the 60 yoke 64 is another yoke 67 extending from the yoke 64 in a direction substantially perpendicular thereto for a purpose which will presently appear. Extending around the 65 pinions 59 and 65 is a sprocket chain 68 so

that when the shaft 31 is rotated the pinion 59 being also rotated, motion is transmitted to the pinion 66 through the chain 68 and sprocket pinion 65.

Extending longitudinally of the telescoping member 58 about midway between the sides thereof is a rack bar 69 fast at what constitutes the upper end of the rack bar to a yoke 70 constituting one of the means for holding the side plates of the telescoping member 58 in spaced relation. Near the lower end the rack bar 69 is fast to another cross piece or yoke 71 connected at its ends to the side plates of the telescoping member 58 and it will be understood that as many of these cross pieces or yokes as may be necessary are employed, short telescoping members needing fewer of these cross pieces than long ones, and in the showing of the drawings the telescoping members are 85 purposely made quite short in order that the scale of illustration may be sufficiently large to be legible. The lower end 72 of the rack 90 69 is thinned so that the teeth approach the rear face of the rack for a purpose which will presently appear. The rear face of the thinned portion 62, that is, the face remote from the teeth, is recessed, as indicated at 73 and within this recessed portion there is secured a spring 74 which may be a flat 95 spring made fast at one end to the rack bar and at the other end this spring carries a pin 75 projecting through the rack bar into the space between two adjacent teeth. This recess adjacent the pin 75 is provided with 100 a shoulder 76 spaced from the end of the spring carrying the pin.

The telescoping member 57 is provided with a rack bar 77 made fast at the ends to yokes 78 serving as spacers for the side 105 plates of the telescoping member 57 and the toothed side of the rack bar 77 engages or is closely adjacent to the rear face of the rack bar 69, this rear face being the face remote from the teeth of the rack bar. The 110 member 58 has an extension 79 above the upper end of the rack bar 69 and the member 57 has an extension 80 above the upper end of the rack bar 77. Fast to another yoke member 78 of the member 57 is one end 115 of a spring 81, the other end of which is formed with a tooth 82 so positioned as to engage the rear face of the rack bar 69 and when the latter has traveled a sufficient distance to bring the recess 73 into coincidence with the tooth 82 the latter will snap into said recess into the path of the shoulder 76 to be engaged thereby, so that then a further elevating movement of the telescoping member 58 will carry the telescoping member 57 with it by reason of the engagement of the toothed end 82 of the spring 81 with the shoulder 76 until ultimately the pinion 66 passes from engagement with the rack 69 into engagement with the rack 77. On 120 125 130

the return movement of the parts a tooth of the pinion 66 engages the pin 75 and forces the spring 74 in a direction to in turn force the spring 81 so that its tooth 82 is 5 without the recess 73 and then the rack bar 69 may drop without further engagement with the spring 81.

The telescoping member 58 is provided at 10 suitably spaced points with brackets 83 between which there extends a bar 84 in position to engage the yoke 67 and so hold the pinion 66 in engagement with the rack bar 69 while the bar 84 is in engagement with the yoke 67. The telescoping member 57 is 15 provided with spaced brackets 85 carrying a bar 86 nearer the center line of the telescoping structure than is the bar 84, but the upper end of the bar 86 bends outwardly with a gentle curve, as indicated at 87, until 20 coincident with the bar 84.

While the telescoping section 57 is being raised by the pinion 66, the bar 84 maintains the engagement of the pinion with the rack bar 69 until the gently curved portion 87 25 of the bar 86 is reached and this is so located that it coincides at the time with the thinned portion 72 of the rack bar 69 and as the telescoping section 57 then begins to rise the cam action of the portion 87 serves 30 to force the pinion 66 into engagement with the thinning portion of the rack bar 69 and ultimately into engagement with the rack bar 77, there holding it, and of course when 35 the parts are telescoped instead of projected the reverse action takes place.

Fast to the end 79 of the telescoping section 58 is a finger 88 having one end in position to engage that arm of the lever 56 remote from the one connected to the chain 55 40 as the parts approach the telescoped position, whereby the lock of the links 51 is broken and the lever 42 is moved by the action of the spring 52 until the clutch shoes 38 are loosened from the gear 30 and the 45 shaft 31 therefore ceases to rotate because uncoupled from the bar, and the parts remain quiescent in the telescoped position.

The upper ends of the telescoping members 58 are designed to carry between them 50 a net 89 which may be in the nature of a life net, such as is employed in connection with fire fighting apparatus, and by projecting the telescoping members this net may be carried to a sufficiently high point above the 55 ground or other support for the apparatus to bring the net within easy jumping distance of endangered persons in case of a fire, and when the endangered persons have landed in the net the apparatus may be 60 lowered and such persons removed. To brace the structure the telescoping members wherever necessary may be joined by connecting beams 90, so that the tendency of the impact of the saved person on landing in the

net to collapse the telescoping members 65 toward a common point is resisted.

It frequently happens that the spread of the net as defined by the telescoping corner posts upholding it is insufficient, wherefore each section 58 on the extension 79 thereof 70 carries an arm 91 which may be so formed as to straddle the end 79, and is carried by an arbor 92 traversing the extension 79 at one end having fast thereto a mutilated gear pinion 93. Fast to the fixed post 48 is an 75 upright rack 94 in the path of the teeth of the pinion 93, so that as the section 58 is lowered to its telescoping position the pinion 93 is given a partial turn by the rack 94. The movement of the pinion is sufficient to rock the arm 91 from a pendent position which it assumes when the parts are telescoped to a position somewhat higher than the horizontal, and as this last named position is approached a pawl 95 pivoted on 80 the upper end of the extension 79 of the section 58 and normally engaged by the rack 95 drops until a tooth 96 on the pawl falls into a notch 97 in the gear or pinion 93, thereby locking the latter against rotation in either 85 direction, the arm 91 then being in the elevated position. When the parts are lowered to the telescoping position the free end of the pawl 95 is engaged by the rack 94 and the tooth 96 is lifted out of the notch 97 just 90 as the rack 94 engages the gear or pinion 93. In order that the pawl 95 may move promptly toward the gear 93, the pawl is controlled by a spring 98 tending to move it 95 toward the gear or pinion 93. The arms 91 100 carry net sections 99 so disposed that when the arms are in the elevated position these sections will constitute continuations of the net 89 around the margins thereof and the outer edges of these marginal nets being 105 more elevated than the inner edges the body of a person landing on the marginal nets will be directed toward the main net 89 and so protected from injury.

Since the structure is elevated by power, 110 it is desirable that when the full elevation is reached the power should be thrown off automatically, and for this purpose the bracket 85 has attached thereto, or is continued as lug 100 so positioned that when the member 115 57 has reached the upper limit of its travel this lug engages the lever 56 on the end of which the chain 55 is attached and lifts this end of the lever to throw the clutch shoes 38 out of engagement with the gear 30 and throw 120 the brake shoes 43 into engagement with the brake member 45, by the spring 52 the momentum of the parts being sufficient to cause the slight movement necessary after the power has been cut off.

If it be assumed that the parts are in the position shown in Fig. 1 when the structure 125 is to be used as a life net support has been

positioned with reference to the endangered persons, the truck engine is not stopped, but is allowed to run continuously and the lever 28 is operated to throw the gear 23 into engagement with the proper one of the pinions 17 or 18. Now the gear wheel 30 is moving in the proper direction and the lever 53 is manipulated to pull the links 51 in a direction to force the clutch shoes 38 into engagement with the gear 30. The shaft 31 begins to rotate and through the connections already described and in the manner already described causes the member 58 to rise, to be followed by the member 57, and this continues unless previously stopped by a manipulation of the lever 53 by hand, until the lug 100 engages the lever 56, thus pulling up on the joined ends of the links 51 and causing the movement of the clutch shoes 38, out of engagement with the gear 30 and the brake shoes 43 into engagement with the brake wheel 45, thereby arresting further upward movement without, however, the necessity of stopping the engine. If the parts are not to be elevated to so great an extent a manipulation of the lever 53 by hand will stop the elevating movement at any point desired. If it now be wished to lower the structure, the lever 28 is moved in a direction to reverse the rotation of the gear 30 and then the lever 53 is moved in the direction to straighten the links 51, thus again coupling the shaft 31 to the gear 30, but the latter now rotating in a direction opposite from that first considered will cause a reversal of movement of the parts until the telescoping is completed and at the last portion of the telescoping action the finger 88 engages the lever 56 and once more breaks the alignment of the links 51, but this movement need only be sufficient to release the clutch shoes 38 from the gear 30, so that movement of the lever 53 in a direction to again clutch the shaft 31 to the gear 30 need be but slight.

It is evident that when the invention is employed in connection with other structures than fire escapes a single telescoping structure with as many telescoping elements as may be desirable can be employed. For instance, let it be supposed that the telescoping structure is to be used as a water tower, then instead of using four, more or less, telescoping structures as would be used with a life net, a single structure will answer for the carrying of hose.

In building construction it is often desirable to elevate and lower building material, and for this purpose a single telescoping structure will usually be sufficient, although this does not preclude the use of more telescoping structures where greater strength and rigidity is desired. Of course, in cases where the invention is used simply as an elevator, the portable feature may be

omitted, although for some purposes it is of advantage.

The height to which the telescoping structure may be projected will depend upon the number of telescoping sections employed. In the drawings there is shown a stationary section and two sections telescoping with respect to the stationary member. It will be understood, of course, that additional telescoping sections may be employed, and while that section which is projected to the highest point will be constructed as is the section in 58 and that section which is projected to the least height will be constructed as is the section 57, intermediate sections will each be provided with a rack bar 69 and an adjusting bar 86 for the pinion 66, so that as a section approaches the upper range of its movement with respect to the pinion 66 the latter will be forced into engagement with the next succeeding rack bar as already described.

While the rack bars are shown as occupying a considerable portion of the thickness of the structure in the drawings, it will be understood that in practice they are not made so bulky in proportion to the other parts as indicated in the drawings, and that any suitable means may be employed for nesting the rack bars so that they occupy less space.

What is claimed is:—

1. An extension tower comprising a series of telescoping elements each inner one being provided with a rack bar in front of the rack bar of the next larger element, an actuating pinion for the rack bars, and means for moving the pinion into and out of engagement with the rack bars successively.

2. An extension tower comprising a series of telescoping elements, each inner one being provided with a rack bar in front of the rack bar of the next larger element, an actuating pinion for the rack bars, and means for moving the pinion into and out of engagement with the rack bars successively, the teeth of a rack bar at what constitutes the lower end thereof approaching the teeth of the next succeeding rack bar which said first-named rack bar overlies.

3. An extension structure comprising a series of telescoping members each provided with a rack bar, the rack bar of an inner member overlying the rack bar of a next successive larger member with the teeth at the end constituting the lower end of the rack bar approaching the teeth of the rack bar which it overlies, a pinion common to all the rack bars and adapted to engage them successively, and means carried by a larger telescoping section for forcing the pinion into engagement with an underlying rack bar on passing from a preceding overlying one.

4. A telescoping extension structure comprising a relatively fixed member, other members of progressively smaller size to telescope within the fixed member, rack bars, 5 one carried by each telescoping member and in progressively overlying relation one to the other, a pinion carried by the relatively fixed member, and means for causing the pinion to move into engagement with each 10 underlying rack on leaving the next successive overlying rack on the projection of the telescoping member.
5. A telescoping extension structure comprising a relatively fixed hollow member, 15 other telescoping members movable into and out of the fixed member and with relation one to the other and each provided with a rack bar with that of an inner member overlying that of the next outer member, the 20 rack bar of an inner member having the toothed portion which constitutes its lower end approaching the toothed portion of the rack bar it overlies, a pinion carried by the relatively stationary member 25 in position to engage the teeth of the rack bars and movable bodily in a direction substantially perpendicular to the movement of the rack bars, and means carried by each telescoping section for causing a bodily 30 movement of the pinion into engagement with the rack bar carried by said section on its passage from the rack bar of the next preceding inner section.
6. A telescoping extension structure comprising a relatively fixed hollow member, 35 other telescoping members movable into and out of the fixed member and with relation one to the other and each provided with a rack bar with that of an inner member overlying that of the next outer member, the rack bar of an inner member having the toothed portion which constitutes its lower 40 end approaching the toothed portion of the rack bar it overlies, a pinion carried by the relatively stationary member in position to engage the teeth of the rack bars and movable bodily in a direction substantially perpendicular to the movement of the rack bars, and means carried by each telescoping section for causing a bodily 45 movement of the pinion into engagement with the rack bar carried by said section on its passage from the rack bar of the next preceding inner section, the pinion being provided 50 with a supporting arm pivotally mounted in the relatively fixed section, and driving means for the pinion extending from the pivot point of the arm to said pinion.
7. A telescoping extension structure comprising a relatively fixed hollow member, 55 other telescoping members movable into and out of the fixed member and with relation one to the other and each provided with a rack bar with that of an inner member overlying that of the next outer member, the 60 rack bar of an inner member having the toothed portion which constitutes its lower end approaching the toothed portion of the rack bar it overlies, a pinion carried by the relatively stationary member in position to engage the teeth of the rack bars and movable bodily in a direction substantially perpendicular to the movement of the rack bars, and means carried by each telescoping section for causing a bodily movement of the pinion into engagement with the rack bar carried by said section on its passage from the rack bar of the next preceding inner section, the pinion being provided with a supporting arm pivotally mounted in the relatively fixed section, and driving means for the pinion extending from the pivot point of the arm to said pinion.
8. A telescoping extension structure comprising a relatively fixed hollow member, 65 other telescoping members movable into and out of the fixed member and with relation one to the other and each provided with a rack bar with that of an inner member overlying that of the next outer member, the rack bar of an inner member having the toothed portion which constitutes its lower end approaching the toothed portion of the rack bar it overlies, a pinion carried by the relatively stationary member in position to engage the teeth of the rack bars and movable bodily in a direction substantially perpendicular to the movement of the rack bars, and means carried by each telescoping section for causing a bodily movement of the pinion into engagement with the rack bar carried by said section on its passage from the rack bar of the next preceding inner section, the pinion being provided with a supporting arm pivotally mounted in the relatively fixed section, and driving means for the pinion extending from the pivot point of the arm to said pinion.
9. An extension tower comprising a series 70 of telescoping members, power means for projecting the telescoping members and including coupling means, an operating member for the coupling means having a normal tendency toward the uncoupled position and provided with locking means for holding it in the active position, a pivoted arm connected to the coupling means, and spaced members carried by different telescoping members in position to move the pivoted 75 arm.
10. An extension tower comprising a series 80 of telescoping members, power means for projecting the telescoping members and including coupling means, an operating member for the coupling means having a normal tendency toward the uncoupled position and provided with locking means for holding it in the active position, a pivoted arm connected to the coupling means, and spaced members carried by different telescoping members in position to move the pivoted 85 arm.
11. An extension tower comprising a series 90 of telescoping members, power means for projecting the telescoping members and including coupling means, an operating member for the coupling means having a normal tendency toward the uncoupled position and provided with locking means for holding it in the active position, a pivoted arm connected to the coupling means, and spaced members carried by different telescoping members in position to move the pivoted 95 arm.
12. An extension tower comprising a series 100 of telescoping members, power means for projecting the telescoping members and including coupling means, an operating member for the coupling means having a normal tendency toward the uncoupled position and provided with locking means for holding it in the active position, a pivoted arm connected to the coupling means, and spaced members carried by different telescoping members in position to move the pivoted 105 arm.
13. An extension tower comprising a series 110 of telescoping members, power means for projecting the telescoping members and including coupling means, an operating member for the coupling means having a normal tendency toward the uncoupled position and provided with locking means for holding it in the active position, a pivoted arm connected to the coupling means, and spaced members carried by different telescoping members in position to move the pivoted 115 arm.
14. An extension tower comprising a series 120 of telescoping members, power means for projecting the telescoping members and including coupling means, an operating member for the coupling means having a normal tendency toward the uncoupled position and provided with locking means for holding it in the active position, a pivoted arm connected to the coupling means, and spaced members carried by different telescoping members in position to move the pivoted 125 arm.
15. An extension tower comprising a series 130 of telescoping members, power means for projecting the telescoping members and including coupling means, an operating member for the coupling means having a normal tendency toward the uncoupled position and provided with locking means for holding it in the active position, a pivoted arm connected to the coupling means, and spaced members carried by different telescoping members in position to move the pivoted arm.

arm in a direction to release the operating member to its normal tendency at the limits of both projection and retraction of the telescoping members.

10. An extension tower comprising a series of telescoping members, power means for projecting the telescoping members and including coupling means, an operating member for the coupling means having a normal tendency toward the uncoupled position and provided with locking means for holding it in the active position, a pivoted arm connected to the coupling means, and spaced members carried by different telescoping members in position to move the pivoted arm in a direction to release the operating member to its normal tendency at the limits of both projection and retraction of the telescoping members, said coupling means being provided with manually operable means constituting the sole means for moving the coupling means to the coupled position.

11. An extension tower provided with telescoping members, power means for projecting and retracting the telescoping members and including a clutch structure and a brake, an operating member for the clutch structure having a normal tendency to move the clutch structure to the unclutched position and to apply the brake, and spaced means carried by different ones of the telescoping members in position to actuate the operating member at the limits of projection and retraction of the telescoping members to cause the release of the clutch member to its normal tendency.

12. An extension tower comprising a series of telescoping members, power means for projecting and retracting the telescoping members and including a clutch structure, an operating member for the clutch structure having a normal tendency in a direction to move the clutch structure to the unclutched position and there maintain it, means connected to the operating member for the clutch structure and movable to release the clutch structure to its normal tendency, and stop members carried by the upper and lower telescoping members in position to engage the last named means to move it in the same direction at both extremes of projection and retraction of the telescoping members to cause the uncoupling of said telescoping members from the power means at said extremes of movement.

13. An extension tower comprising a relatively fixed member and telescoping members movable successively into and out of the fixed member, actuating means for the telescoping members, power means for the actuating means, a clutch interposed between the power means and the actuating means for coupling the power means to and uncoupling the power means from the actu-

ating means, a lever controlling the clutch, a toggle locking and actuating means for the lever, another lever connected to the toggle and movable to flex the toggle, and stop members carried by the inner and outer telescoping members in position to engage the last-named lever to flex the toggle at the respective limits of extension and retraction of the telescoping members.

14. An extension tower comprising a relatively fixed member, telescoping members movable into and out of the fixed member, a shaft carried by the fixed member near the lower end thereof when the said fixed member is in operative position, a clutch carried by the shaft, means for actuating the shaft through the clutch, actuating means for the telescoping members operated by the shaft, an operating lever for the clutch, a toggle member controlling the clutch lever, and means for flexing the toggle to uncouple the clutch at the extremes of movement of the telescoping members in either direction.

15. An extension tower having a relatively fixed member and telescoping members carried thereby, a rack carried by the fixed member, a pinion carried by one of the telescoping members, a pawl carried by the telescoping member having the pinion and movable into and out of locking engagement with the pinion, and an arm actuated by the pinion when engaged by the rack.

16. An extension tower having a relatively fixed member and telescoping members carried thereby, a rack carried by the fixed member, a pinion carried by one of the telescoping members, a pawl carried by the telescoping member having the pinion and movable into and out of locking engagement with the pinion, and an arm actuated by the pinion when engaged by the rack, said rack being located in the path of the pawl to disengage the same from the pinion when the latter is engaged by the rack.

17. A life net structure comprising a suitable support, spaced telescoping members carried thereby, connections between said telescoping members for their simultaneous actuation, a life net extending between and carried at the corners by the telescoping members, rockable arms carried and actuated by the telescoping members and extending outwardly therefrom at substantially bisecting relation to the corners of the life net, and nets carried by the rockable arms supplemental to and in surrounding relation to the outer edges of the life net.

18. A life net structure comprising a suitable support, spaced telescoping members carried thereby, means for the simultaneous actuation of the telescoping members, a life net extending between the telescoping members and at the corners connected to respec-

tive telescoping members, other nets in surrounding relation to the first named net and exterior to the telescoping members and supporter thereby, and means for moving the 5 last named nets to a pendent position when the telescoping members are retracted and an elevated position when the telescoping members are expanded, said last-named means and the telescoping members having 10 coacting connections for causing the stated movements of the second named nets.

19. A life net structure comprising a suitable support, telescoping members carried thereby, connections between said telescoping 15 members for their simultaneous actuation, a life net carried by the telescoping structures, rockable arms carried by the telescoping structures, and nets carried by the rockable arms in position to the exterior and 20 supplemental to the main net, the telescoping members and arms being provided with coacting parts for moving the arms and nets carried thereby to a substantially pendent position when the telescoping members are 25 retracted and to elevate the arms and spread the nets carried thereby when the telescoping members are projected.

20. In a life net structure, a series of supporting members, interconnecting means therefor for operating the telescoping members simultaneously, a net extending between and carried at the corners by the 30

telescoping members, a rocker arm extending outwardly from each telescoping member in a direction to define substantially the 35 same angle to each of the two adjacent sides of the respective portion of the life net, nets carried by the rocker arms exterior to the first-named net and wholly surrounding the latter, means for raising the rocker arms 40 from the normally pendent position to an upwardly extending position to spread the supplemental nets, and means for locking the rocker arms in the elevated position.

21. A life net structure comprising a 45 wheeled vehicle, spaced cradles carried thereby, a frame pivotally mounted at the front and rear on said cradles, rack segments carried by the frame, pinions engaging the racks, an operating shaft carried by 50 the cradles and in turn carrying the pinions, spaced expandable and retractile supports carried by the frame at the forward and rear portions thereof, a life net mounted on and extending between said supports, and 55 actuating means for the supports also carried by the frame.

In testimony, that I claim the foregoing as my own, I have hereto affixed my signature in the presence of two witnesses.

JOHN L. ACKLEY.
